Inventor

UNITED STATES PATENT OFFICE.

PERCY ROBERT DOBSON, OF CALGARY, ALBERTA, CANADA, ASSIGNOR TO BELL EQUIPMENT COMPANY LIMITED, OF CALGARY, ALBERTA, CANADA.

DOOR-OPERATING MECHANISM.

Application filed July 6, 1928. Serial No. 290,817.

This invention relates to door operating mechanism adapted to open and close doors mounted on hinges or rollers, and so constructed as to be operated from within by means of cranks.

A further object of my device is to lock the doors in both the open and the closed positions, and a still further object is to provide means remote from the door for opening and closing the said door which would be particularly advantageous in garages, warehouses or the like.

While doors of garages and warehouses have been particularly mentioned, the use of my device is not limited to doors but may be applied to gates, or other devices where remote control is desirable.

Referring to the drawings in which similar characters refer to similar parts—

Fig. 1, is a plan showing the device applied to folding doors, in which two sections are folded back on each door jamb. It also shows in dotted lines the door in the open position.

Fig. 2, is a partial elevation showing the bell cranks and the cable operating the said bell cranks.

Fig. 3, is a detail of the hand operating device and the method of adapting thereto the remote controller.

Mounted upon the doors 7, of a garage near the top, and extending from the sides towards the middle, are slotted members 8, and rigidly secured upon the door frame just above the doors are brackets 9.

Bell cranks 10, are rotatably mounted in the brackets 9, one end of which engages in the slotted members 8, and on the other end of the said bell cranks pulley wheels 11, are secured.

The bell cranks are so arranged that when the doors are closed they are practically at right angles to the door, and in this position the doors cannot be opened from the outside, and when the doors are opened the cranks being similarly related the doors cannot accidentally swing.

A pulley 12, is mounted upon an operating shaft 13, which shaft is rotatably mounted in brackets 14, and 15, the brackets being mount-

ed upon the interior wall of the garage, and on the lower end of the shaft 13, a handle 16, is pivoted. A cable 17, passes around the two pulley wheels 11 and also around the pulley 12, on the operating shaft 13, this cable being secured at a pre-determined point to each of the pulleys to prevent slippage, and the size of the pulley 12, is such that half of one revolution will open the doors and one half of one revolution in the reverse direction will close them.

To give remote control, a secondary pulley 18, is mounted upon the shaft 13, a similar pulley 19, being secured upon a duplicate operating shaft 20, which shaft is mounted in suitable brackets 21, located within the garage. The operating shaft 20 has a handle 22 pivoted to the base thereof, and a cable 23, passes around the pulleys 18, and 19, being secured thereto similarly to the cable 17. A turnbuckle 24, is provided for adjustment purposes by means of which unnecessary slack in the cable is eliminated.

What I claim is—

1. Door operating mechanism comprising in combination with doors or the like, slotted members mounted upon the said doors, cranks engaging the slotted members, brackets mounted upon the door frame with cranks rotatably mounted therein, pulley wheels mounted upon the said cranks, an operating mechanism suitably located in relation to the said door, cable connections between the said operating mechanism and the cranks, and means for applying power from the said operating mechanism through the cables to the cranks to open and close the doors.

2. Door operating mechanism comprising a door with slotted members mounted thereon, bracket members mounted upon the door framing, cranks rotatably mounted in the said brackets engaging the slotted members of the door, cable connections to the said cranks from an operating device, an operating device consisting of a rotatable rod mounted in suitably located brackets, the said rod being provided with operating handle, all substantially as described.

PERCY R. DOBSON.
